(57) **CLAIM**

The ornamental design for a remote control, as shown and described.

DESCRIPTION

FIG. 1 is a front, bottom perspective view of a remote control design showing our new design.

FIG. 2 is a front view of a remote control.

FIG. 3 is a rear view of a remote control.

FIG. 4 is a left side view of a remote control.

FIG. 5 is a right side view of a remote control.

FIG. 6 is a top view of a remote control.

FIG. 7 is a bottom view of a remote control; and,

FIG. 8 is a rear, top perspective view of a remote control.

1 Claim, 8 Drawing Sheets

FIG. 1

FIG. 2

FIG. 3

FIG. 4

FIG. 5

FIG. 6

FIG. 7

FIG. 8
